CURTAIN FIXTURE

Richard V. Aiello and Robert Aiello, Wampun, Pa.

Application September 13, 1948, Serial No. 49,044

1 Claim. (Cl. 248—262)

1 This invention relates to a shade and curtain fixture and it is an object of the invention to provide means easily adjustable within certain limitations for securing the fixture in working position without the use of nails, screws or the like.

Another object of the invention is to provide a fixture of this kind including rod together with a bracket on the rod adjustable along the rod for supporting a curtain rod and/or a drapery rod.

The invention consists in the details of construction and in the combination and arrangement of the several parts of our improved shade and curtain fixture, whereby certain advantages are attained, as will be hereinafter more fully set forth.

In order that our invention may be better understood, we will now proceed to describe the same with reference to the accompanying drawings, wherein:

Figure 1 is a fragmentary view in top plan of an end portion of a fixture constructed in accordance with an embodiment of the invention;

Figure 2 is a detail sectional view taken substantially on the line 2—2 of Figure 1;

Figure 3 is a detail sectional view taken substantially on the line 3—3 of Figure 1;

Figure 4 is a view in perspective of the holding bracket as comprised in Figure 3 and unapplied; and

Figure 5 is a fragmentary view in front elevation of the holding bracket.

In the embodiment of the invention as illustrated in the accompanying drawings, 1 denotes an end portion of an elongated rod which is in cross section in the form of a flattened C with the longitudinal slot 2 thereof rearwardly disposed. The rod 1 may be of a single length or comprise a member of telescopically engaged sections whereby the rod may be lengthened or shortened.

Contacting the outer face of the rod 1, at each end portion thereof is the intermediate or base plate 3, of a bracket B. The upper and lower margins of this plate 3 are defined by the rearwardly disposed and reverted flanges 4 which snugly straddle the rod 1 from above and below, as shown in Figure 2 of the drawings. These flanges 4 frictionally engage the associated marginal surfaces of the rod 1 to effectively hold the bracket B in desired or selected adjustment in the rod but also readily permitting the required shifting of the bracket B along the rod 1 to obtain such adjustment.

2 The opposite extremities of the plate 3 of the bracket B are defined by the outstanding plates 5 each of which telescopically engages within a lateral extension 6 of either a curtain or a drapery rod 7. Each of these plates 5 has struck therefrom a tongue 8 to assure desired frictional engagement of the plate 5 within an extension 6.

In the drawings only a single rod 7 is illustrated but the manner of use of a second rod is believed obvious.

Each end portion of the rod 1 and preferably inwardly of an applied bracket B has associated therewith a supporting bracket S. This bracket S includes a substantially straight top arm 9 of required dimensions and which is provided at one end with a depending tang 10 which is adapted to be forced into the upper surface of the top or crown piece of a window frame or the like whereby the bracket S may be effectively maintained in desired position without the use of nail or the like.

The opposite or forward end portion of the arm 9 is continued by a downwardly disposed rounded extension 11 which terminates in an arm 12 disposed downwardly and inwardly. The arm 12 is continued by a short straight arm 14 which is substantially at right angles to the arm 9. The arm 14 is adapted to have direct contact with the outer face of the member with which the tang 10 engages or to a suitably provided surface therebelow.

The intermediate portion of the arm 14 of the bracket S has struck outwardly therefrom and at right angles thereto the outwardly disposed T heads or plates H. These plates or heads H are aligned transversely of the arm 14. The shank 15 of each of the heads or plates H is snugly engaged through the slot 2 of the rod 1 while the cross head 16 of each of the heads or plates H snugly engages within the bore of the rod 1. While the heads or plates H snugly and frictionally engage the rod 1 yet they permit the bracket S to be shifted along the rod 1 to a selected position as determined by the requirements of practice.

Mounted on the rod 1 at a suitably spaced point inwardly of the bracket S is a shade bracket A of such type as may be desired.

From the foregoing description it is thought to be obvious that a shade and curtain fixture constructed in accordance with our invention is particularly well adapted for use by reason of the convenience and facility with which it may be assembled and operated.

We claim:

A curtain and shade fixture, including an elongated supporting rod substantially C-shaped in cross-section with the slot rearwardly disposed, a supporting bracket for said rod comprising a top arm for securement to a window frame or the like, said arm being continued downwardly and inwardly to provide a bearing arm substantially at right angles to the top arm, and a pair of T-shaped elements cut and out-turned from the opposite side edges of said bearing arm for engagement within the rod. **10**

RICHARD V. AIELLO.
